UNITED STATES PATENT OFFICE.

CHARLES EDGAR FRITTS, DECEASED, LATE OF ONEONTA, NEW YORK, BY JOSEPHINE H. FRITTS, ADMINISTRATRIX, OF ONEONTA, NEW YORK, ASSIGNOR, BY MESNE ASSIGNMENTS, TO JOHN D. MYERS, OF PHILADELPHIA, PENNSYLVANIA.

METHOD AND MEANS FOR RECORDING AND REPRODUCING VARIATIONS IN LIGHT.

1,203,191.

Specification of Letters Patent.

Patented Oct. 31, 1916.

Original application filed October 22, 1880, Serial No. 19,313. Divided and this application filed June 22, 1912, Serial No. 705,353. Renewed March 1, 1916. Serial No. 81,553.

To all whom it may concern:

Be it known that CHARLES EDGAR FRITTS, now deceased, but formerly a citizen of the United States residing at Oneonta, in the 5 county of Otsego and State of New York, did invent a new and useful Improvement in Methods and Means for Recording and Reproducing Variations in Light, of which the following is a specification.

10 This invention relates to recording variations or pulsations in sounds, light or electric currents in a permanent or tangible form and reproducing the same at will not merely at the instrument alone, but also at any other 15 instrument suitably connected therewith.

The present application is a division and continuation of the original application, Serial No. 19,313, filed October 22, 1880, and relates to one of the forms of record shown 20 and described in said original application.

The present invention includes the application of photography and electricity for recording and reproducing the variations or pulsations above mentioned.

25 For convenience of description the apparatus disclosed for utilizing the record produced will be called a phonograph, but it is to be expressly understood that it is not the intention to limit the scope of the invention 30 to what is commonly known as or done by the so-called phonographs or to narrow or restrict the scope of the invention in any way, but the term is used merely for convenience.

35 The novel features of the invention will be apparent from the following description taken in connection with the accompanying drawings.

In the drawings, Figure 1 is an edge view 40 of a speaking diaphragm having a shutter mounted thereon such as may be used in carrying out the invention. Fig. 2 is a view partly broken away showing a speaking diaphragm carrying a shutter, a source of light 45 and a roller carrying a sensitive strip exposed to said light through an opening controlled by said shutter. Fig. 3 shows at the left a plan view of the sensitive strip and rollers and at right an enlarged plan view 50 of a portion of the strip having the photographic record thereon. Fig. 4 shows two forms of shutter mounted on diaphragms

which may be used in carrying out the invention. Fig. 5 is a plan view of a strip having thereon a sinuous record produced 55 by the shutter shown in Fig. 4. Fig. 6 shows two additional forms of shutters which may be used. Fig. 7 shows the form of record produced by the shutter shown in Fig. 6. Fig. 8 is a vertical sectional view of one 60 form of apparatus arranged for making the negative pattern and moving it along by hand in carrying out the invention. Fig. 9 is a diagrammatic view showing means for reproducing and utilizing an opaque record 65 by reflected light. Fig. 10 shows an electric circuit having a selenium bar therein adapted to be affected by light from my record. Fig. 11 is a similar view showing a flat selenium cell with a lens for concentrating the 70 light from the record on it. Fig. 12 shows a photographic pattern having records thereon laterally separated by a longitudinal blank strip. Fig. 13 shows two selenium cells arranged for exposure through a single opening 75 to produce alternating current. Fig. 14 shows diagrammatically a record such as will be produced by the upper shutter shown in Fig. 4. Fig. 15 is a sectional view of an apparatus which may be used either for 80 making or utilizing the record. Fig. 16 is a view of a divided shutter and two selenium bars for producing alternating current. Fig. 17 shows a modified form of divided shutter mounted as a key. Fig. 18 is a view of 85 another arrangement. Fig. 19 is similar to Fig. 13 showing the electrical connections more clearly. Fig. 20 is a general view of the apparatus disclosed in Fig. 8 but more in detail showing more clearly the arrangement 90 and connection of the parts. Fig. 21 is a horizontal section on the line $\alpha-\alpha$, Fig. 20.

Broadly speaking, this invention is based upon the laws governing the behavior of certain substances when exposed to the action of radiant energy. The action of actinic rays of light upon certain substances producing effects known as photographic need not be explained, as that method of utilizing radiant energy is well known.

100 Another mode of action of radiant energy is in changing electrical resistance, as shown by the action of light upon certain substances, notably selenium, whose electrical

conductivity is well known to be greatly increased by exposure to light. Amorphous phosphorus is similarly affected and other substances are known which may be employed in like manner. This action of radiant energy is utilized for suitably controlling and varying electrical currents in different ways, but preferably by arranging the sensitive substance in a current-controlling device 5 of an elongated form in the path of the rays from the source of light, and varying the quantity of light which falls upon it by varying the length of the illuminated portion of it.

15 A third mode of action of radiant energy is the vibration of thin plates under the influence of varying light directed on them, the plates being made from suitable material, especially hard rubber.

20 The invention is illustrated as applied to the production of sound records but it is to be expressly understood that it is not the intention to thereby limit the scope of the invention to what is known as or done by the 25 so-called "phonographs" or to narrow or restrict the scope of the invention in any way.

In carrying out this invention a record of varying phenomena is first made and said record is then used to reproduce the original 30 phenomena.

In making the negatives as records of sound, the sound to be recorded is caused to impinge upon a vibrating diaphragm, which is properly damped and arranged, as will be 35 readily understood by those versed in telephony. To the center of the diaphragm d , Fig. 1 is fixed a vertical screen or shutter s of mica or other light and stiff material, being attached by its center, and the outer 40 corners rounded off a little to prevent their contact with the diaphragm during its backward vibrations, or to the left. It projects out at right angles to the plane of the diaphragm, and in this particular form is made 45 opaque to prevent the passage of any light through it. Fig. 2 is a vertical plan view; s is the shutter, d the diaphragm, l is a powerful light throwing a beam of nearly parallel rays across to the screen or partition S , 50 which has a long, narrow slit m in it, through which the light passes and strikes the prepared surface, which in this case is represented as a strip of sensitized paper, fed at a regular speed over the rollers $R R$. As the 55 diaphragm shutter s in this form normally stands, its edges shut the light off from one-half of the slit, and in vibrating it covers up more or less of the strip, according to the extent of the vibrations. The paper strip 60 being carried along behind the slit m , Fig. 3, the edge of the shutter will describe a curved line at the junction of the part e^1 , not acted upon by the light, and e , which is acted upon, and by proper treatment the latter may be 65 dissolved away or otherwise made transpar-

ent, in any well known way, as will at once be understood by photographers.

By varying the relative distances of the light, the shutter, and the slit or sensitive surface from each other, the apparent amplitude of the sound waves as recorded on the sensitive surface, can be increased without changing their forms. This method of amplifying the vibrations is often important, and can be applied for strengthening pulsations or variations in light or electrical currents, as well as in sounds.

If, instead of an opaque shutter on the diaphragm, we leave a vertical transparent strip across said shutter, the light will reach 80 the paper strip behind the screen only through the intersection of the two slits in front of it, forming merely a square spot of light, as shown by Fig. 4 at the intersection of the two slits n and m . The vertical slit on 85 the mica should make the light beam of about the same width as the stationary horizontal slit in the screen. As the diaphragm vibrates and the paper is moved along, we produce (after dissolving out the parts exposed to 90 light, blacking the rest, soaking in oil or otherwise rendering it transparent) a narrow, transparent curve on the paper strip, as represented in Fig. 5. Instead of the vertical strip, we may use a transparent spot at 95 the point which will fall on the center of the stationary slit when the diaphragm is still as seen at n' on the upper shutter shown in Fig. 4. This also makes a negative strip, like Fig. 5.

100 Another way is to have two shutters, one on the diaphragm as before, only larger, and the other stationary, and parallel to but not touching it. These shutters are painted, or otherwise treated to make them 105 opaque up to a certain point, the rest being transparent. These opaque edges are notched, so that at their junction they lap so as to form square or diamond spaces which are transparent, as in Fig. 6, where s 110 is the vibrating shutter, and s^1 is the stationary one. In this case, the slit in the screen before the paper strip is placed vertically, and the paper is fed past it horizontally. Consequently, as the movable 115 shutter s is vibrated to and fro before the other, these transparent squares or diamonds become alternately larger and smaller. But they should neither quite meet nor be quite extinguished even by the greatest vibrations 120 of the diaphragm. The result is to produce on the opaque negative strip transparent lines of varying width, one of which is shown enlarged in Fig. 7. If a narrow beam of light is sent through it, it will be 125 more or less obscured at different places along the strip, i. e., the quantity of light allowed by the transparent parts of the strip to pass through the slit will be increased or decreased, corresponding exactly to the 130

pulsations of the diaphragm (or the sound waves) not only in number and intensity, but also in the form or manner of vibrating.

It will thus be observed that the negative 5 may be made alike across its whole width and its transparency varied so as to be more or less opaque at different parts of its length. Or an opaque strip may be similarly varied from white through all the shades to black 10 so that a given cross-section of the strip will reflect more or less light at different points.

At 2, Fig. 7, is seen a fine opaque line in the middle transparent strip. This is made 15 by placing a fine wire across the center of the stationary slit m , to stop the light and indicate the center of the negative strip. Its convenience will be manifest. In practice the stationary notched shutter s^1 is not 20 necessary, as the slit m is sufficient in connection with the vibrating notched shutter as seen by the lower figure in Fig. 6 which shows how the lateral vibration of the shutter with its transparent notch will vary the 25 amount of light passing through the stationary slit m . These patterns or negatives, and others which can be made by the above described method, are suited for different uses. It is evident that when a correct negative 30 is once obtained, perfect copies can be produced not only by photographic but also by ordinary printing processes, or even by mechanical means, at a merely nominal cost, even for the most elaborate negatives.

Having thus explained the principles of the present invention, Fig. 8 represents an apparatus which has been devised for carrying out the method and producing the record. At A is a roll of the prepared sensitized strip, wound upon a bobbin, which is 35 mounted in journal bearings in any convenient way. This strip may be of any suitable thin and flexible material, which may be strong fine paper, but what is known as paper parchment is preferred, although 40 many other substances, may be used. It should be covered with a thin film made very sensitive to light, by any of the instantaneous processes employed in photography, although a dry process will be most 45 convenient with this form of sensitized strip. After being properly coated and sensitized, it should be carefully dried, rolled up, and protected from light or damp till 50 ready to use it. It may be thus coated and sensitized either before or after being cut up into strips of width suitable for use, but in the latter case care must be taken in the cutting not to disturb the adhesion of 55 the film to the strip. A suitable width is $\frac{1}{2}$ or $\frac{3}{4}$ inch, and the length will of course be governed by convenience, or the choice of 60 the operator.

The roll A is free to turn, being held only 65 by the spring l , pressing upon it sufficiently

to prevent it from turning faster than the strip is needed. From A, the strip passes over the flanged rollers R, R, Figs. 2, 3 and 8; at R^1 is a rubber-faced roller which presses the paper strip between itself and R, 70 tightly enough to prevent the slipping of the strip. It also fits between the flanges of the roller enough to carry that along with it. If desired, it can also press lightly on the roller A^1 , to assist in rewinding the strip 75 upon it. To this roller can be applied the power which feeds the strip along before the slit m in the screen or partition S. For experiment, or common telegraphic purposes, a crank may be attached to the roller 80 R ^{1} or R, as shown in Fig. 8, or the strip may be otherwise fed by hand. But when accuracy is required, some motor should be employed which will give the negative a perfectly uniform and known rate of speed. 85 These are not new, and need not be described, as they form no part of my invention. The motor may be attached to or contained in the box or frame of the phonograph, or otherwise connected, as preferred. 90

The strip being thus fed along at a uniform speed, it is wound upon a second roller A^1 , or may simply be fed loosely into the bottom of the box or case of the phonograph. It will now remain unchanged, if kept from 95 light and damp, for days or even weeks,—or, on the other hand, it may be at once developed, intensified, fixed, or otherwise treated, to render the image permanent, according to the process employed or the effect desired. All of which will be at once understood by those versed in photography, who will be enabled, from the foregoing description, to readily make a negative strip 100 having the characteristics required, and will 105 probably prefer the gelatin-bromid process. If the paper seems to have a greasy nature, it may before applying the bromid emulsion, be coated with a 4 per cent. solution of white of egg, to which sufficient chrome 110 alum has been added to give it a slight bluish tinge. This will insure the film adhering perfectly, but it will seldom be required if a good quality of paper or parchment is used. These strips being fixed, they 115 may be treated and used in different ways. The parts acted upon by light may be made transparent, and the rest blacked and rendered more opaque, and the strip used by transmitting light through it; or the strip 120 may be left opaque, and used by reflected light,—in which case the parts acted upon by light should be made as white or brilliant, and those yet not acted upon as black and absorbent of light as possible, all of which 125 can be done by any one out of many well known ways, and detailed directions are not necessary. For example, a strip to be used by transmitted light may have the dark parts blacked with carbon ink, flexible black 130

varnish, or otherwise, and the lights rendered transparent by dipping in castor oil thinned with absolute alcohol.

The finished strip being again wound upon the wheel or roller A and properly arranged in the phonograph, we can reproduce the original variations in the first beam of light, in another beam of light, by feeding the strip before the slit *m* at the same speed as when making the negative, and throwing the beam of light through it as it passes the slit. To do this, the diaphragm *d* with its shutter is removed. The square chamber which contained the diaphragm is now empty or free, and allows the light *l* to shine unobstructed across it, to and through the slit *m*, onto and through the strip which is rapidly fed before it, whereby the light which passes through the strip is varied in precisely the same manner as the original beam of light was varied by the shutter on the diaphragm *d*, *i. e.*, the greater the proportion of the strip which is transparent, the greater the amount of light which is passed through it, and vice versa (see Fig. 3). This light can now be used to produce corresponding variations or pulsations in sound, electric currents, magnetic attractions, etc. as desired. This varying light can be converted into sounds in different ways. It may be passed through a plano-convex or rather plano-cylindrical lens *p* or any suitable optical device, to widen and disperse it properly, and be thrown directly upon a thin, hard-rubber diaphragm *D*, properly arranged for speaking or giving out sounds. Or, in place of the lens *p*, a selenium bar or cell may be arranged to receive the light and thereby vary a current of electricity flowing through it, as shown at *p* in Figs. 10, 11 and 15, which current may then be conducted to a suitable telephone, which is substituted for the diaphragm *D*, and the sounds will be produced by it with any desired loudness. Or the current may be conducted by wire to any other instrument or place, in the same way as in telegraphy, and there converted into sounds or utilized for any other purpose, as in Fig. 15, where a current from *D* is represented as conveyed to a telephone *T'* at one place and to an electrical receiver of any suitable kind *El'* at another place.

When selenium is used for receiving the light and varying an electric current, it may be either in the shape of a bar *p* covering the slit *m*, as shown in Figs. 10 and 15, or that of a flat cell *p'* in Fig. 11, where the light passing through the negative or pattern *P* and the slit *m* is converged by the lens *p* to a focus, upon the selenium cell *p'*. Or, for producing an intermittent current it may consist of two selenium cells or bars suitably arranged as shown in Fig. 13. The same arrangement is used in connection with

patterns like Figs. 3, 7 and 12 for producing alternating currents or undulating currents of alternately opposite polarity. The two cells are arranged end to end with their approximating ends at the central line 70 of the pattern strip so that one cell or bar is opposite one half of the slit *m* and the other bar or cell opposite the other half. Each cell is arranged to send whatever current flows through it in a direction opposite 75 to that of the current from the other cell, in any well-known or suitable manner and each may be supplied with its current from different ends or sections of the same battery or from separate batteries, as shown in Figs. 80 16 and 19, where the two sections of the selenium are inserted in derived circuits or branches of the main circuit *ww*. In either case, the electric current is arranged to flow through the selenium by proper conducting 85 wires and the varying quantity of light which falls upon the selenium will correspondingly vary the current flowing through it, as is well known to electricians.

A strip or pattern, like Fig. 12, thus employed, will produce an alternating current, whose changes of strength and polarity will be sudden or instantaneous—for each section of the cell will be at once lighted for the whole length of the signal or form on the 90 strip, then as suddenly shut off from all light, and the other cell or section will be lighted and operated by the form on the opposite half of the pattern strip. A pattern like Fig. 3 or 7, however, produces the 95 changes of strength and polarity gradually. When designed to be used with a divisional selenium cell, the patterns should, of course, be made by a divisional shutter on the diaphragm, as shown in Fig. 16. In using such 100 a shutter to produce negatives, it should be arranged so that the central vertical line or division of the shutter will fall on the central line of the slit *m*, which should also be made preferably in two parts in different 105 planes, as shown by the position of *r* and *r'* in Fig. 16 or 17. When arranged as in Fig. 16, the opaque part *s* of the shutter stands between the light and the part *r'* of the slit and *S'* covers up the slit *r*, as will be understood from Fig. 18, where the parts are so arranged. Now, when the shutter vibrates to the right, *s*' uncovers more or less of slit 110 *r*, and when moving to the left, the part *r'* of the slit is similarly exposed by the removal of *S*. The sensitive surface being fed down past the slit, a pattern is produced like Fig. 3 or 7 but with the two halves independent, and possibly, dissimilar,—each corresponding to the movements of its own 115 half of the shutter. By now moving this pattern (when finished) past the slit again after arranging a sectional selenium cell behind it with each section of the selenium behind the corresponding section of the cell 120

(and the shutter being now moved back out of the way) we shall produce alternating currents whose variations in strength and polarity will correspond to the original vibrations of the shutter and, therefore, of the force which moved it—the principle involved in making and using the pattern being precisely the same as already described. I would here remark that the method of constructing selenium cells is now well understood and any known or suitable method or arrangement may be employed.

By arranging the diaphragm d , or its shutter s , to be operated manually, feeding the strip slowly and vibrating the shutter in a manner similar to that used in sending the ordinary Morse signals with the ordinary key, the result would be a strip like Fig. 12, with transparent lines across it. The shutter can, of course, be actually arranged on a sort of key and be vibrated manually before the slit m to intercept the light properly. Fig. 17 shows this device adapted for producing alternating currents. The parts s and s' are opaque, the rest of the shutter transparent. The black bodies r and r' represent the two sections of the slit m which are normally covered or protected by the opaque portions s and s' . But when the key K is operated to move the shutter to the right it uncovers the section r , and vice versa, thus producing the pattern precisely as already described, only it is now done manually instead of automatically. By arranging the shutter like Figs. 4 and 18, to be moved in both directions from the center and to different distances for the different letters or signals, a strip like Fig. 12 would be made. Fig. 18 shows the key or lever K for moving the shutter, the proper distances being indicated by the scale y^2 . The springs y keep it normally in its central position and when moved to either side it uncovers one of the sections of the slit m precisely as described for Fig. 17 and the further the key is turned on its central pivot the more of the slits or openings are uncovered by the shutter and the greater the length of time that the beam of light will be allowed to pass through to the sensitive surfaces behind the slit. Such a strip prepared in either way can then be run through my instrument at almost unlimited speed and the signals will be perfectly produced by the light being varied during its passage through the strip and then falling on two selenium bars or strips or other current-controlling devices arranged behind the slit m , producing correspondingly varying currents, which are then sent over the line or other currents induced by them sent instead to another phonograph or to one of my telephones or other apparatus, as shown at $E1$ in Fig. 19, where P is the pattern or strip moving past

the slit m in the partition S , and r and r' represent the two sections of the slit with the sectional current-controlling device arranged behind it—each section, when lighted, sending a current of opposite polarity through the circuit. When the speed is so great that the sounds or signals are unintelligible to the eye or ear at the receiving station they may first be recorded by one of my phonographs and the negative so prepared be then run through another phonograph, (or telephone), at the ordinary speed. In this way, the line wire can be utilized to its utmost capacity in speed for conveying the messages which may require a number of instruments to afterward speak or deliver them in the usual manner. Several currents may be conducted through the seleniums and so manipulated and transmitted simultaneously to different points.

Fig. 13 represents the arrangement for transmitting signals by said strips with a single long slit m in the phonograph except that the strip or negative P is fed past the slit m transversely instead of lengthwise of it as it would appear to be in the drawing. m is the narrow slit long enough to cover the length of the two selenium bars p and p' , each being inclosed and protected from all light except that which passes through the slit and the negative strip P . Each bar has proper wires to conduct the current through it which are so connected up that each bar directs the current which flows in it through the line in an opposite direction, and their resistances are such that no current (or a very slight one) flows through either of them as long as they are kept in the dark. But immediately that the negative strip admits light to either bar, its resistance is lessened and the current flows through that bar to the line or to the primary coil of an inductorium which sends the induced current to line or to any other device as the case may be—the strength of the current being in proportion to the portion of the bar, thereby exposed to the light. The electrical connections are, as more fully shown in Fig. 19, or they may be arranged in any other suitable or well-known manner. The longer the transparent part of the strip or signal, the more of the bar is lighted up, and the stronger the current which flows through it. When the other bar is illuminated the same effect is produced but the current is sent through the line or circuit in the opposite direction—all of which will be readily comprehended and effected by electricians.

When using an opaque strip or negative, the sound waves, or, rather, the variations of light produced by them are recorded in the same way as already described. But to reproduce those variations the strip is fed along with the printed or formerly sensi-

tive side outward in the path of a beam of light by which it is powerfully illuminated and the light reflected from it is utilized instead of transmitted light. Fig. 9 shows an arrangement which may be employed. l is the light which passes through the alum-water cell 2 through the tube 3 and illuminates the moving strip or pattern 4 or P . 5 is a tube with blackened interior, each end having an aperture corresponding to the slit m which would be used with a transparent pattern and so directed toward the strip that only the light from that part of the strip which would be covered by the slit m can pass through both apertures—all of which will be readily understood by photographers. This light is then received by the lens or other suitable optical device p and properly thrown upon the diaphragm D as before or the lens p may be replaced by the selenium bar or cell and the diaphragm D by one of the telephones, etc., exactly as before described for transmitted light. The distance of the illuminating arrangement from the negative strip is merely sufficient to thoroughly light up the field covered by the tube 5 . Tubes 3 and 5 may be of any suitable size, length, and material, all of which may be left to the judgment of the operator, who should arrange the apparatus according to good photographic practice.

Fig. 20 shows the general arrangement of the apparatus in more detail than Fig. 8. $E7$ represents an electrical apparatus capable of vibrating the diaphragm D when a telephonic, telegraphic or other suitable current is passed through it and thereby vibrating the shutter s placed in the path of the beam of radiant rays from l here shown as an electric lamp, and thus varying said beam in accordance with the extent and character of its own movement. The beam thus varied is in the first instance thrown upon the sensitized strip P fed down from reel A over guide roller R before the opening or slit m onto another reel A' . The strip having been properly treated to bring out and fix the image thus obtained and render it suitable for use as a pattern, as before described, it is again wound upon reel A and its end hooked to reel A' . The apparatus $E7$ is moved back far enough to take shutter s out of the beam of radiant rays which then pass through the negative and are varied thereby as they had been previously varied by the shutter s , after which they fall upon a selenium cell or other suitable apparatus p' , all as heretofore explained.

Fig. 21 is a horizontal section through the lines $x-x$ of Fig. 20, showing the light and lenses l , alum cell 2, shutter s , cylindrical lens p which converges the light laterally to a long narrow streak where it passes

through the opening m to strip P . The set-screws t' t'' adjust the forward position of the block t^2 on apparatus $E7$ to bring the shutter s to the right point. p^2 is a small selenium cell which serves to automatically start off the strip P when the phenomenon occurs which is to be recorded. The shutter s is caused to vibrate, as already stated, and thereby uncovers the cell p^2 , allowing the light which had previously been stopped by the shutter to fall upon the cell and by increasing its conductivity an electric impulse is sent through the starting magnet M' . This immediately pulls up the armature and lever L and raises the pawl 8 which had previously held the reel A' , whereupon the reel is suddenly revolved and draws the strip P past opening m until the sound or other phenomena ceases, when the shutter becomes still, the current substantially ceases to flow through the cell p^2 and magnet M' , the lever L drops and the reel A' is stopped. When reproducing the recorded phenomena the lever L is lifted manually by a cord a running over a pulley through an aperture to the outside at some accessible point, where it can be pulled when desired. The current of the cell p^2 can also be sent through induction coil I and transmit the message if desired to a telephone T at the same time that it is being recorded on P .

The light employed for making the negative should be strongly actinic, and may be direct sunlight, or electric or other artificial light having sufficient actinic power for instantaneous photography. It should be arranged in a chamber W , preferably with a reflector or other means for making the rays nearly parallel. At 2, Fig. 8, they pass through a glass cell filled with alum water, to stop the heat without diminishing the light. They then pass through an aperture of suitable size, across the diaphragm chamber, where they are manipulated by the shutter s , and through the slit m , as already described. For using the negative, so strong a light will not always be needed, and a good kerosene lamp will answer for most ordinary purposes. Gas light is not suitable, unless a steady flame can be obtained, as a flickering light will interfere with the perfection of the speaking. For purposes requiring accuracy, however, a light should be used having ample actinic power, and the stronger the better. No harm can be done by having a light unnecessarily strong as it cannot be strong enough to do any harm.

Having described the invention what I claim and desire to secure by Letters-Patent is—

1. The combination with a movable sensitized surface, of means for moving said surface with regulated timing, means for ex-

- posing said surface periodically to light on different sides of a longitudinal line to produce photographic effects thereon in two adjacent rows.
- 5 2. The combination with a camera, of a movable sensitized surface therein, means for moving said surface with regulated timing, shutter mechanism to control the admission of light to different lateral portions 10 of said surface, and means for operating said shutter mechanism to form on said surface a plurality of longitudinal laterally separated records of variations in light.
3. An apparatus for taking photographic 15 impressions suitable for reproducing in proper sequence and with proper timing variations in light due to changing phenomena having in combination a camera, a single sensitized flexible strip therein, means for moving said strip with regulated timing, and means mechanically controlled for admitting light to laterally different portions of the strip to form separate longitudinal records on the same strip.
- 25 4. An apparatus for taking photographic 20 impressions suitable for reproducing in proper sequence and with proper timing variations in light due to changing phenomena having in combination a camera, a single sensitized flexible strip therein, means for moving said strip with regulated timing, shutter mechanism for controlling the admission of light to laterally separated portions of said strip, and means for operating 30 said shutter mechanism with proper timing to form on said strip a plurality of longitudinal records of variations in light.
5. An apparatus for taking photographic 35 impressions suitable for reproducing in proper sequence and with proper timing variations in light due to changing phenomena having in combination a camera, a single sensitized flexible strip therein, means for moving said strip with regulated timing, a 40 divided shutter for separately controlling the admission of light to laterally different portions of said strip to form two photographic records thereon, and means for operating said shutter.
- 50 6. A record of variations in light capable 45 of use in reproducing those variations with proper timing consisting in a surface having thereon a plurality of photographic records of variations in light side by side 55 and in proper sequence.
7. A record of variations in light capable of use in reproducing those variations with proper timing consisting in a surface having thereon two longitudinal rows of photographic impressions of variations in light 60 in proper sequence with a blank space between said rows.
8. A record of variations in light capable of use in reproducing those variations with proper timing consisting in a surface having thereon two longitudinal rows of separated photographic impressions of variations in light in sequence taken in rapid succession with proper timing.
9. The method of recording successive 70 variations in light, which consists in moving a sensitive surface with regulated timing, and taking two closely adjacent longitudinal rows of photographic impressions on said surface.
10. The method of recording and reproducing successive variations in light which consists in taking two longitudinal slightly separated rows of photographic impressions of variations in light in proper sequence on 80 a single sensitive surface developing and producing from said surface a permanent record and projecting light modified in succession by the impressions in said rows on said permanent record to a receiving surface with proper timing to reproduce the 85 original light effects.
11. The method of recording and reproducing successive variations in light which consists in taking two longitudinal slightly 90 separated rows of photographic impressions of variations in light in proper sequence on a single elongated flexible strip having a sensitive surface, developing said strip to fix said light effects, projecting light 95 through said strip to a receiving surface modified in accordance with said photographic impressions in the two rows and moving said strip with regulated and proper timing to reproduce on said receiving surface the original variations in light.

In testimony whereof I affix my signature in presence of two witnesses.

JOSEPHINE H. FRITTS,

*Administratrix of the estate of Charles
Edgar Fritts.*
